UNITED STATES PATENT OFFICE

109,951

DESIGN FOR AN AIRPLANE

John Pavlecka, Detroit, Mich.

Application September 14, 1934, Serial No. 53,283

Term of patent 7 years

To all whom it may concern:

Be it known that I, John Pavlecka, a citizen of the United States, residing in Detroit, in the county of Wayne and State of Michigan, have invented a new, original, and ornamental Design for an Airplane, of which the following is a specification, reference being had to the accompanying drawings, forming part thereof.

In the drawings,

Fig. 1 is a side elevational view of an airplane of any size, showing my new design.

Fig. 2 is a plan view shown to a somewhat reduced scale; and

Fig. 3 is a front view shown on the same scale as Fig. 2.

I claim:

The ornamental design for an airplane, substantially as shown and described.

JOHN PAVLECKA.
